GARMENT HANGER

Leonard A. Young, Detroit, Mich.

Application May 5, 1941, Serial No. 391,935

11 Claims. (Cl. 223—83)

This invention relates to improvements in garment hangers.

The main objects of this invention are:

First, to provide a garment hanger which is of extremely simple and inexpensive construction, yet which is characterized by substantial strength and ruggedness.

Second, to provide a garment hanger of the type described including a garment supporting yoke which is fabricated in its entirety of foldably laminated, suitably conformed and compressed paper stock suitably formed to impart thereto a high degree of strength and resistance to bending or distortion.

Objects relating to details and economies of the invention will appear from the description to follow. The invention is defined in the claims.

Preferred embodiments of the invention are illustrated in the accompanying drawings, wherein:

Fig. 1 is a view in front elevation illustrating a hanger of the invention.

Fig. 2 is a top plan view of the same structure.

Figs. 3 to 8, inclusive, are enlarged fragmentary views in transverse section illustrating successive steps or manipulations in the formation of the stock of the hanger yoke, Fig. 8 illustrating the material in final form and being in section on a line corresponding to line 8—8 of Fig. 1.

Fig. 9 is a view in front elevation illustrating a modified form of garment hanger provided with a yoke and a transverse garment supporting strut in accordance with the invention.

Fig. 10 is a top plan view of the structure shown in Fig. 9.

Fig. 11 is an enlarged fragmentary view in section on a line corresponding to line 11—11 of Fig. 9.

Fig. 12 is a plan view illustrating the blank employed in the formation of the hanger shown in Fig. 9.

Fig. 13 is a top plan view illustrating the yoke and strut member formed from the blank of Fig. 12 prior to bending and securing the arms thereof.

The garment supporting hanger of the present invention is characterized mainly by the simplicity and economy of its construction notwithstanding the remarkable strength and resistance to distortion or bending of the garment supporting yoke or arms thereof. Referring to Fig. 1 of the drawings the reference numeral 1 indicates the hanger which consists of a downwardly curved garment supporting yoke 2 and a supporting hook 3 operatively attached thereto.

The yoke 2 is conformed of a web or length

of folded paper stock of the cross-section shown in Fig. 8, which cross-section results from manipulating an elongated sheet of paper stock of a suitable grade or gauge successively through the various steps illustrated in Figs. 3 to 8.

Thus in Fig. 3 the reference numeral 4 designates the single ply paper blank for the yoke, the original flat condition thereof being indicated in dotted lines. From this position the opposed side edges thereof are first bent upwardly at a right angle as illustrated in solid lines in Fig. 3, then inwardly through 90° into parallelism with one another and pressed into contact with the center of the blank forming the two-ply strip 41 illustrated in Fig. 4. If desired the paper stock may be impregnated with a suitable adhesive or other setting material to increase the stiffness of the final product.

From the position illustrated in Fig. 4 the folded sheet is again folded and pressed along its center line through 180° to the quadruple-ply condition illustrated in Fig. 5 and designated 42, and following this the quadruple-laminated outline is bent into U-shape, i.e., from the dotted line position of Fig. 6 to the solid line position, it being understood that these operations described are preferably successively and continuously performed in a single pass through an appropriate die conformed at various points to impart the successive cross-section described. The partially formed U-shaped article then has the downwardly extending legs 43 thereof offset inwardly and downwardly at a right angle along lines 44 spaced from the side edges thereof to produce the key-shaped outline shown in solid lines in Fig. 7, and as a final step the upper surface is squeezed downward on these offsets to crimp said legs inwardly and upwardly and compress the cross-section vertically, resulting in the T-shaped configuration or outline shown in Fig. 8. This leaves a rounded top garment surface or flange 45 of substantial area, a bottom vertical web or rib 46 which has substantial stiffness by reason of the 8-ply construction thereof, so as to reinforce the yoke, and a hollow center 5 for the reception of a part of the hanger hook 3 in the manner to be described.

Referring to Fig. 1, it will be noted that the shank 6 of hook 3 is offset laterally at 7, then bent reversely at 8 to provide a clamping jaw and terminating in the upwardly directed extremity or bill 9. The upper surface 41 of the yoke stock is perforated at 10 and the curved bill of the jaw introduced therethrough into the hollow interior 5 of the yoke, following which the hook is

shoved lengthwise of the jaw 8 for frictional gripping and embedding engagement of the latter with the upper flange portion of the hanger yoke. This is a simple and effective means enabling the yoke and hook to be quickly and conveniently associated in firm, displacement resisting relation to one another.

It will be noted that the bottom rib 46 of the yoke has indentations 91 formed therein in order to produce the desired curved outline of the yoke. These do not detract from the resistance to bending of the latter.

In Figs. 9 and 10 I illustrate a modified form of hanger fabricated of the laminated folder paper stock described above. In this form the hanger yoke has a pair of outwardly and downwardly divergent arms 11 and a transverse horizontal garment supporting strut 12 integral with the arms. The free ends of the arms are gripped at the apex of the hanger by a clamping loop 13 on the hook 14 so as to hold the structure in assembled or erected position. It will be noted that in the embodiment of Fig. 9 the rib or web 15 on both the arms 11 and the yoke 12 is disposed beneath the upper or flange portion thereof, the latter affording a smooth supporting surface of substantial area and the rib or web strongly reinforcing the arms and yoke against bending. In order to accomplish this the original blank 16 for the folded stock is formed in the manner illustrated in Fig. 12, with the pairs of opposed notches or recesses 17 located therein at the areas at which the arms 11 are to join struts 12. The procedure of folding the blank to its final cross-section is performed as illustrated in Figs. 3 to 8, and it will be appreciated that following this treatment the portions of the stock adjacent the recesses 17 will lack the ribs 15 found on the arms and strut. In other words, the width of the strip at these notched areas is such that following the molding and compressing operations the strip is in flat condition. Only two plies are present at these areas, resulting from folding of the flat single-ply strip along its center line only. This enables the stock to be bent freely at these points to bring the arms 11 together. Care should be taken that prior to the bending assembly the ribs 15 on the arms 11 extend oppositely from those on the strut 12 as illustrated in Fig. 13, so as to insure that the ribs or webs will be disposed beneath all the garment supporting surfaces, both arms and strut, in the final disposition of the arms.

The above constructions are both characterized by simplicity and economy in materials and they may be produced in quantity at negligible cost. Notwithstanding this the hangers have ample strength for their intended purpose and may be used time and time again; however, disposal thereof does not involve any appreciable waste of money.

I have illustrated and described my improvements in embodiments which I have found very practical. I have not attempted to illustrate or describe other embodiments or adaptations as it is believed this disclosure will enable those skilled in the art to embody or adapt my improvements as may be desired.

Having thus described my invention, what I claim as new and desire to secure by Letters Patent, is:

1. A garment hanger comprising a bowed multiply paper yoke of transversely flattened section and having a central longitudinal bottom rib, and formed of a strip of multi-folded paper stock,

the plies of which are adhesively secured together, the multiply strip being conformed into the flattened section with angularly disposed edge portions thereof disposed side by side and constituting the said longitudinal rib, and a wire suspending hook having a shank terminating in a yoke engaging loop having an elongated free arm, said yoke having an opening at the top thereof receiving said elongated arm, the loop clampingly engaging the top wall of the yoke.

2. A garment hanger comprising a bowed multiply paper yoke of transversely flattened section and having a central longitudinal bottom rib, and formed of a strip of multi-folded paper stock, the plies of which are adhesively secured together, the multiply strip being conformed into the flattened section with angularly disposed edge portions thereof disposed side by side and constituting the said longitudinal rib, and a suspending hook for said yoke.

3. A garment hanger comprising a yoke of transversely flattened section and having a longitudinal bottom rib, said yoke being formed of a multiply strip of fibrous stock, the plies of which are adhesively secured together, the multiply strip being conformed into the flattened section with rounded top and sides with angularly disposed abutting edge portions constituting the said longitudinal rib, and a suspending hook for said yoke.

4. A garment hanger comprising a paper yoke of transversely flattened section and having a longitudinal bottom rib, and formed of a fibrous strip conformed into the flattened section with angularly-shaped edge portions thereof disposed side by side in abutting relation and constituting the said longitudinal rib, and a suspending hook for said yoke.

5. A garment hanger of the type described and a hook, and garment supporting arms secured to said hook, said arms being fabricated of a plurality of superposed laminae of a single longitudinally folded strip of paper stock, said laminae being conformed to a generally T-section having a transverse flange and a vertical rib disposed downwardly beneath the transverse flange, said flange and rib each including multiple laminae, the laminae at the top and bottom of said flange and the sides of said rib being substantially compressed to meeting and reinforcing engagement with one another.

6. A garment hanger of the type described and a hook, and garment supporting arms secured to said hook, said arms being fabricated of a plurality of superposed laminae of paper stock conformed to a generally T-section having a transverse flange and a vertical rib disposed downwardly beneath the transverse flange, said flange and rib each including multiple laminae, the laminae at the top and bottom of said flange and the sides of said rib being substantially compressed to meeting and reinforcing engagement with one another.

7. A garment hanger comprising a bowed yoke formed of a web of paper folded parallel to its length a plurality of times to provide a laminated multiply strip, said strip being conformed to a tubular cross section providing a tubular garment supporting surface of substantial width and a downwardly projecting reinforcing rib of double the number of plies as the body portion, and a hook provided with a shank having a terminal engaging internally of said yoke, the yoke having an opening receiving said terminal.

8. A garment hanger comprising a yoke

formed of a web of paper folded on itself parallel to its length a plurality of times to provide a laminated multiply strip, said strip being conformed to a flattened cross section providing a garment supporting body portion of substantial width and a downwardly projecting reinforcing rib of double the number of plies as the body portion, and a hook provided with a shank having a terminal engaging internally of said yoke, the yoke having an opening to receive said terminal.

9. A garment hanger comprising a yoke formed of a web of paper folded on itself parallel to its length a plurality of times to provide a laminated multiply strip, said strip being conformed to a flattened cross section providing a compact, substantially solid garment supporting body portion of substantial width and a downwardly projecting substantially solid reinforcing rib of double the number of plies as the body portion, and a suspending hook secured to said yoke.

10. A garment hanger having downwardly divergent garment supporting arms fabricated of

a sheet of paper stock folded on itself a plurality of times, the outer edges of said stock being bent at an angle to the central portion and crimped inwardly and compressed relative to the central portion to provide a substantially solid horizontal flange and bottom reinforcing rib, the rib being disposed downwardly and beneath the horizontal flange to substantially reinforce the latter, said flange providing a garment supporting surface of substantial area.

11. A garment hanger having downwardly divergent garment supporting arms fabricated of a plurality of plies of paper stock, the outer edges of said stock being bent at an angle to the central portion and crimped inwardly and compressed relative to the central portion to provide a substantially solid horizontal flange and bottom reinforcing rib, the rib being disposed downwardly and beneath the horizontal flange to substantially reinforce the latter, said flange providing a garment supporting surface of substantial area.
